MACHINE FOR STRAIGHTENING AND SIZING CASTINGS, FORGINGS, STAMPINGS, OR THE LIKE

Clarence W. Bell, Lakewood, Ohio

Application December 4, 1945, Serial No. 632,678

7 Claims. (Cl. 153—33)

1

My present invention comprises a novel machine for straightening and sizing castings, forgings, formed stampings, formed stampings after welding, and other classes of formed or molded articles that necessitate straightening or sizing after the original production thereof by casting operation, stamping, forging, or similar operation.

My present machine is adapted for performing straightening or sizing operations upon articles of various types so long as the material from which they are produced has sufficient inherent elasticity to admit of the straightening action thereof.

To those who are versed in the arts of casting, stamping, forging, and similar forming operations usually performed on metal articles of one kind or another, it is well known, for instance, that castings as they come from the mold are usually not true to the forms required to be taken thereby when actually used for the final purpose of their production. This is likewise true in relation to forgings, stampings, and similarly formed articles of manufacture. Thus, after the production of castings, in many instances, the castings are required to be straightened or sized to bring them down to the final form within the tolerances permitted in relation to the exact shape thereof established by the production drawings for such article. Present day methods pursued for straightening and sizing castings involve frequently many different operations by machine or hand in order to straighten and size the ultimate casting to render it usable for the purposes for which it may be produced. Castings are frequently required to be machined by hand; and also, in many instances, they are straightened or sized by machine or hand hammer operation which latter may produce hidden fractures or weakened parts in the castings, and indeed sometimes break the casting completely, rendering it useless. These various heretofore used straightening and sizing operations are not only expensive and time-taking, but occasionally do not actually enable the obtaining of an ultimate product which is accurate within reasonable tolerances upon comparison of same with the original measurements prescribed by the manufacturer's drawings. The foregoing is similarly true in regard to forgings, metal stampings, and similarly formed articles, so that it is a desideratum of importance to avoid the objectionable practices customarily employed today to which I refer above and largely utilized for the purposes of my present invention by the use of which such practices may be avoided.

2

With the foregoing in mind, the machine designed by me and hereinafter set forth more in detail as to structure and operation is operable to receive the casting, for instance, as a whole, and by the application of an even gradual pressure twist and squeeze back into the required shape, predetermined by the original measurement drawings of the article, the said casting, so that when the twisting, squeezing, and similar operation has been performed the casting will be accurately straightened or shaped, and set to size that is finally required for its useful purpose.

More specifically stated, my present machine comprises an assembly of mechanical devices with operating means therefor, which devices include accurately built dies which conform to the final accurately dimensioned castings, stampings, forgings, or like article, which dies are adapted to be actuated when the casting, forging, or stamping as completed by the casting, forging, or forming processing thereon respectively, is bodily emplaced in my machine and subjected to the straightening and sizing operation that the machine is adapted to perform. And the operation of my machine is susceptible of being effected without causing die marks on the particular article which is being straightened or sized, without any distortion or injury to the material of such article, and with a minimum of spring back of such material, which minimum is within the drawing tolerances of the production drawings from which the particular article is made.

Having in mind the foregoing objects of my invention, therefore, reference is made to the following description for a complete understanding of the construction of my invention, in conjunction with the annexed drawings showing one embodiment of my invention as designed for the purpose of straightening and sizing castings.

In the accompanying drawings:

Figure 1 is a vertical sectional view showing a machine structured in accordance with my invention illustrating a casting therein and showing the various parts of the machine as they are adjusted for the application of the final pressures required to straighten and size the particular casting which is being handled.

Figure 2 is an enlarged fragmentary sectional view bringing out more clearly the arrangement of certain lateral acting pressure members forming a part of the upper die of my machine, the same being the male die carried by a suitable upper supporting plate.

Figure 3 is a detail sectional view taken on the

line 3—3 of Figure 2 and being a section through one of the pressure members.

Figure 4 is a view in elevation of one of the pressure members such as illustrated in Figure 3, alone.

Figure 5 is a sectional view somewhat similar to Figure 2, but showing only the upper complementary pressure members and disclosing a modified means for mounting the pressure members upon the supporting member of the upper die of which they form a part.

Figure 6 is a detail section view on the line 6—6 of Figure 5.

Figure 7 is a view similar to Figure 1, but illustrating the machine in what may be stated as open condition before the upper and lower dies are brought together and before the casting which the dies are adapted to straighten and size is introduced into the machine.

Figure 8 is a view taken about on the section line 8—8 of Figure 1, the section looking downwardly.

Figure 9 is a sectional view, fragmentary in nature, taken about on the line 9—9 of Figure 1 looking in the direction of the arrows.

Figure 10 is a perspective view of a typical casting such as is shown in Figure 1 and in Figure 8, and which will be sized and straightened by means of the operation which is illustrated as being performed in Figure 1.

Figure 11 is a top plan view looking down upon the hollow body or die holder of the machine and showing the bottom plunger actuated plate in position therein, the other superposed parts of the machine being removed.

Figure 12 is a side view or edge view of the bottom plunger actuating plate.

Figure 13 is a plan view of said bottom actuating plate alone.

Figure 14 is a plan view of the yielding lower pressure plate on which the lower die members are supported.

Figure 15 is an edge view of the plate illustrated in Figure 14.

Figure 16 is a view of the casting shown in Figure 10 with arrows applied to illustrate the direction of the pressure forces applied to the casting in the straightening and sizing operation performed by my machine.

In the following description of my machine, the embodiment thereof for straightening and sizing of a predetermined construction of casting as the casting comes from the mold by which it is originally formed is illustrated. To this end the die members, to be more fully described later, are especially designed for the handling of such casting, but it will be understood that such members would be modified in construction and shape in the event that they are employed for operations of straightening different other shapes of castings or for straightening and sizing forgings, stampings, or other similarly formed articles of manufacture.

Referring primarily to Figure 7, my machine will be seen to comprise a suitable support 1 upon which is mounted a hollow body 2 shown in Figure 10 to be of somewhat square form looking downwardly thereon, said body 2 forming a holder for the lower die members shortly to be described. On the base 1 and arranged within the hollow portion of the body or holder 2 is a spring supporting plate 3 connected with a cylinder member 4 that passes through the base 2, by bolting means designated 5. On the plate 3 are carried a series of springs 6 which are interposed between the

member 3 and the upper yieldable pressure plate designated 7, the dimensions of which are somewhat the same as those of the plate 3, the two members 6 and 7 having recesses therein in which the opposite ends of the springs 6 are seated.

On its lower side the plate 7 carries centrally thereof a hardened bearing member 8 provided with a socket to receive the upper ball head 9 of a vertically movable plunger rod 10, which plunger rod may be actuated mechanically, hydraulically, pneumatically, or otherwise, to effect vertical upward and downward movements thereof, pipe 10a supplying a fluid to cylinder 10 to actuate piston therein carrying the rod 10.

Supported upon the upper surface of the pressure plate 7, which upper surface as seen in Figure 14 is shown to be slightly beveled in opposite directions at opposite sides thereof, are the rockable, openable, or relatively movable die shoes 11, said shoes being two in number in the present construction of my machine. The die shoes 11 are seen to be of somewhat angular form comprising the vertical side members 11a and the bottom horizontal portions or members 11b, the latter being adaptable to be rockingly supported, so to speak, upon the adjacent upper surface portions of the pressure plate.

Now the die shoes 11 are of peculiar construction to support certain die members in that they are carried upon the pressure plate 7 and are susceptible of a relative tilting or rocking movement while carried by the member 7. The adjacent inner edges of the horizontal portions 11b of the shoes 11 are designed to be interlocked by the provision of a male transverse tongue 12 on the right hand shoe 11 as seen in Figure 7, and the provision of a female groove or recess 13 which is adapted to receive the said tongue or projection 12. The parts 12 and 13 fit loosely together in order to admit of the relative rocking action of the two shoes 11 which are illustrated, and it will be apparent that vertical movement of the plunger rod 10 is adapted to raise and lower the member 7 so as to correspondingly elevate or permit downward movement of the shoes 11 supported on the latter.

Another feature of construction of my machine to be particularly noted is the fact that the inner surfaces of the walls of the body or holder 2 as seen particularly in Figures 1 and 7 are inclined downwardly and inwardly so that they constitute virtually cams. Complemental to the cam formation shown at 2a on the drawings, and referring to the holder 2, the outer sides or surfaces of the shoes 11a are similarly formed of downwardly and inclined structure to provide wedging cam parts 14 adapted to slide on and relatively to the cam portions 2a of the holder 2 for a purpose to be more fully set forth herein-after.

The die shoes 11 are adapted to carry die members 15 which are constructed to accurately conform with the lower side portions of a casting in accordance with the accurate dimensions which the final casting is required to have for its use for the purpose for which it is designed, subject only to the tolerances specified for the particular article. For the purpose of attaching the die members 15 to the shoes 11 I employ suitable screw bolts 16 between the portions 11a of the shoes 11 and the die members 15, and other screw bolts 17 between the lower portions 11b of the shoes and the said die members 15. Describing the lower die means further, it may be noted that the same virtually comprises a sectional die

made up of complementary members 15 as illustrated. Two die sections are shown as employed, for which reason only two of the shoes 11 are utilized, but it is within the purview of my invention that a greater number of the die sections 15 be availed of, dependent upon the nature of the casting to be sized or straightened, and the different angles at which pressure must be applied to such casting for performing the straightening or sizing operation. Thus the holder 2 is shown to be of generally square form, making it readily adaptable for the reception of four die shoes 11, in which event there would be a corresponding number of sections of the lower die means utilized directly secured to such shoes, and, if desired, the outer surfaces of the die shoes would be made of cam formation for a purpose to be hereinafter set forth, and for which purpose the cam formations 14 are shown in the drawing.

The die members 15 are formed with opposite recesses, see Figure 1 and Figure 7, in which are disposed the ends of expansion springs 18, said springs 18 preferably located near the upper and lower portions of the die members, and acting to separate the die members and the shoes 11 when the pressure plate 7 is in its upraised position and so held by means of the actuating plunger 10, see Figure 7.

The die members 15 on their female or receiving portions are equipped with inserts 19 in the form of hardened metal buttons the heads of which are designed to exert pressure forces on certain parts of the casting, which are to be straightened or brought to size, the action of these parts on the casting being clearly illustrated in Figure 1. The parts of the casting with which the inserts 19 cooperate, as seen in Figure 1, may be members that are required subsequently to be drilled to provide journals or any like parts.

It is notable also that carried on the upper surfaces of the members 11a of the die shoes are other hardened inserts 20 the upper surfaces of which are designed to cooperate with corresponding inserts 21 carried by the upper die supporting or holding member or plate 22, see Figures 1 and 7. The die holding plate 22 carries the upper male die 23, and said plate 22 is supported upon or at the lower end of a plunger 24, which may be hydraulically operated also, to produce vertical movement thereof in carrying the upper male die member 23 into and out of cooperating relation in respect to the lower die members 15. The plate 22 may be connected detachably with the plunger 24 by means of a dovetail tongue and groove connection shown at 25.

Having in mind the construction of my lower die members 15 and shoes 11, it is notable that the upper die member 23 will be equipped with hardened pressure inserts 26 similar to those designated 19 which are carried by the lower die members 15. In fact, the inserts 26 are designed to cooperate with the inserts 19, as quite apparent by the method of depicting the operation of my machine in its final straightening and sizing operation according to Figure 1. In order to obtain lateral pressure functions in certain actions of the upper male die member 23 to obtain certain sizing and straightening pressure actions on the casting introduced into my machine for the purpose hereinbefore referred to, I equip the upper die member 23 with certain expandible or wedging pressure parts. As seen in Figure 7 the die member 23 has a depending projection 23a, and on this projection are mounted yieldable pressure

elements 27 which are in the form of complementary wedges or camming parts that slide up and down upon the converging surfaces of the projection 23a at opposite sides of which they are arranged. The members 27 may be interlocked with the projection 23a by means of a dovetail tongue as seen in Figures 2 to 4 inclusive said tongue designated 28 and operating in a groove on the adjacent side of the projection 23a. A stop plate 29 prevents displacement of the members 27 from the projection 23a by abutment action in respect to a portion of the tongue 28, as quite evident from the illustration in Figures 2 to 4 inclusive. Suitable expansion springs are mounted in recesses in the upper ends of the members 27 and in shoulder portions of the projection 23a and are designated 30 and seen best in figure 2. The laterally shifting camming pressure pieces or members 27 are in duplicate and are located near the upper portion of the male die 23. For the purpose of handling the straightening and sizing of the casting shown, the lower end portion of the die 23 will be equipped with a single camming pressure member 31 substantially of the construction previously described in reference to the member 27 and similarly acted upon by means of a spring 32, so that the member 31, like the member 27, will normally be projected downwardly and will yield upwardly as the die member 23 moves down into the female die members 15, so that the camming actions on the parts 27 and 31 will be in a lateral pressure direction.

Figures 5 and 6 illustrate merely a modification of my invention in which I utilize link devices 33 for connecting the camming members, designated 27a in this instance, to the projection 30 of the upper or male die of my machine.

With the foregoing description I have set forth the primary and essential features of construction of my machine, and I will now describe the operation of the same.

The parts of the machine of my invention will be assumed to be in the position of Figure 7. At this time the shoes 11 and die members 15 are elevated and will be supported yieldably upon the springs 6 through the action of the pressure plate 7. The die member 23 is uplifted and the die parts may be described as in their opened condition or position. Any lifting pressure on the rod or member 10 will be released through release of the hydraulic controls for this member.

The casting as it is received from the mold is now arranged in the space between the lower die members 15 on the shoes 11 and generally distanced in proper position for operation thereon to effect the straightening and sizing action.

Thereupon, the plunger 24, carrying the plate 22, is caused to lower and move downwardly the upper male die 23, the members 27 and 31 of which are in their lower position. When the upper die 23 makes contact with the upper side portions of the casting, a downward pressure is exerted upon the casting, upon the die members 15, and upon the shoes 11 supporting said die member. This action of movement downwardly of the shoes 11 causes a cooperation between the cam surfaces 14 and 2a of the members 11 and 2 respectively, and the casting is moved downwardly as a whole, and an even gradual pressure applied thereto by which to squeeze and twist the parts of the casting into the proper form and shape predetermined by the original production dimensional drawing defining the appropriate shape and size of said casting. In this manner

the casting is finally shaped and set to the accurate size required with the only allowance that for customary tolerances. Under these conditions the parts of my machine will be in the condition represented by Figure 1, and when the male die 23 is lowered, it is evident that the pressure members 27 and 31 will be caused to move upward by contact with portions at the upper side or sides of the casting so as to obtain the necessary pressure forces that may be exerted laterally necessarily in order to get the proper set and final form of certain elements of the casting. The action of the parts 27 and 31, of whatever number may be used, will be automatic in the closing together of the several die members 15 and 23, and the downward movement of the parts 11 and 15 of course will lower the pressure plate 7 as permitted by the yielding resistance of the expansion springs 6.

The sizing and straightening operation of the casting having been completed in the manner described, the next operation is to remove the sized and straightened casting. This operation is performed simply by raising the plunger 24 with the plate 22 and male die 23 and thereupon, by the means provided, raising the rod or member 10 to elevate the pressure plate 7 and correspondingly elevate the shoes 11 and female die 15. This action causes a release of the pressure between the cams 14 and 2a of the parts 11 and 2 respectively, and the springs 18 will thereupon move the die members 15 apart and permit of ready manual displacement of the casting which has now been shaped and sized to the correct dimensions required for subsequent operations to be performed that may be necessary to complete the construction of the casting.

It is of course to be understood that the members 27 or 31, or equivalent members, may be differently arranged at various angles than those shown in the drawings, dependent upon the kind of casting which is to be operated upon. Figure 16 illustrates the casting and shows by arrows the distribution of the pressure forces by which the casting is finally set true to its required ultimate shape.

It is contemplated that the machine of my invention may be employed as an inspection testing fixture or machine for inspecting castings for defective welding, or for similar inspection of forgings to find defects that might later show up in service.

By the use of my machine, many manual or machine finishing operations that are required today in conjunction today with rough castings are wholly avoided, and it is obvious that the production of castings with the use of my machine may be tremendously increased in so far as obtaining final castings which are true to size and necessary ultimate shape.

Resetting of the relation of the upper and lower die members may be accomplished by replacement of the pressure inserts 20 and 21 in an obvious manner. These members and the inserts 19, and also the pressure parts 27 and 31, may be replaced, if unduly worn, as when large rims of castings are straightened and sized by my machine.

The principles of use and operation of my machine as above explained are similarly availed of in straightening and sizing forgings, stampings, stampings with welds, etc., the necessary dies for such purpose being utilized.

In Figure 16 the somewhat diagrammatic illustration shows, by arrows, the directions of

pressure straightening and twisting forces obtained in the operation of my machine, for straightening and sizing a casting of the kind depicted. Obviously, different castings, forgings, stampings, etc., will require the use of die members designed particularly for them. In Figure 9 I show movable pressure die members 35 and guiding and spring means after the manner of the structure of Figure 2, but which cannot be seen in Figures 1 and 7 as carried by the main die members 23. These members would act to size the part of the casting designated X in Figure 16.

Having thus described my invention, what I claim as new and desire to secure by Letters Patent of the United States is:

1. In a straightening and sizing machine, in combination, a holder comprising a hollow body, movable die shoes therein having bottom rocker portions, lower relatively movable die members

20 carried by said shoes, a support above the holder, a die member on said support complemental to the lower die members, and means to close the said die members together and simultaneously move the lower die members relatively to each other, combined with yielding means rockably supporting the bottom rocker portions of the die shoes for the said movement of the die members.

2. In a straightening and sizing machine, in combination, a holder comprising a hollow body, a base member on which the holder is mounted, a plurality of die shoes in said holder having adjacent ends, the shoes and holder having coacting parts to cam the shoes from open to closed positions after a formed article is disposed therebetween, and means to move the shoes downward to close the same, combined with a yieldable pressure plate in the holder and on which the shoes are carried, the adjacent ends of the shoes being rockably interlocked.

3. In a straightening and sizing machine, a holder comprising an outer hollow body having downwardly and inwardly inclined camming walls, die shoes having outer cam surfaces coacting with said walls and mounted in the holder, a yieldable support in the holder on which the shoes are rockably carried, a base member on which the holder is mounted, the die shoes being interlocked at their lower portions for rocking

45 spreading movement at their upper portions, lower die members on the die shoes, spring means between adjacent portions of the shoes to separate them when they are elevated, a support above the holder, and movable downward toward the

50 holder, and upper die members on the support to enter between the lower die members on downward movement of the support to effect rocking pressure movement of the lower die shoes and die members thereof toward each other and toward the upper die members.

60 4. A machine as claimed in claim 3, in which the shoe support is combined with pressure means operating upwardly from said base member to move said shoe support for coaction with the interlocking portions of the die shoes to cause rocking apart of the die shoes and lower die members.

65 5. A machine as claimed in claim 3, in which the shoe support is combined with pressure means operating upwardly from said base member to move said shoe support for coaction with the interlocking portions of the die shoes to cause rocking apart of the die shoes and lower die members, said pressure means including a pressure plate on said base member having a bearing 70 against the interlocked portions of the die shoes,

and lifting means bearing upwardly against said pressure plate.

6. In a straightening and sizing machine, a holder comprising an outer hollow body having downwardly and inwardly inclined camming walls, die shoes having outer cam surfaces coacting with said walls and mounted in the holder, a yieldable support in the holder on which the shoes are rockably carried, a base member on which the holder is mounted, the die shoes being interlocked at their lower portions for rocking spreading movement at their upper portions, means for spreading said shoes, lower die members on the die shoes, a support above the holder, and movable downward toward the holder, upper die members on the support to enter between the lower die members on downward movement of the support to effect rocking pressure movement of the lower die shoes and die members thereof toward each other and toward the upper die members.

7. In a straightening and sizing machine, a holder comprising an outer hollow body having downwardly and inwardly inclined camming walls, die shoes having outer cam surfaces coacting with said walls and mounted in the holder, a yieldable support in the holder on which the shoes are rockably carried, a base member on

which the holder is mounted, the die shoes being freely floatably mounted for rocking spreading movement at their upper portions, lower die members on the die shoes, spring means between adjacent portions of the shoes to separate them when they are elevated, a support above the holder, and movable downward toward the holder, and upper die members on the support to enter between the lower die members on downward movement of the support to effect rocking pressure movement of the lower die shoes and die members thereof toward each other and toward the upper die members.
